ANTHONY Z. MICIULIS, OF CHICAGO, ILLINOIS.

AIR-PUMP.

1,241,872.

Specification of Letters Patent.

Patented Oct. 2, 1917.

Application filed November 16, 1916. Serial No. 131,781.

To all whom it may concern:

Be it known that I, ANTHONY Z. MICIULIS, a subject of the Czar of Russia, residing at Chicago, in the county of Cook and State of Illinois, have invented certain new and useful Improvements in Air-Pumps, of which the following is a specification.

The present invention relates to a mechanism for compressing air and transmitting the air so compressed to a storage tank.

The principal object of the invention is to use a series of pivoted compression members, associated with each of which is a weighted member. The compression members will be rocked by a power driven shaft, which rocking will cause the weighted members to slide back and forth upon a suitable mounting. The weighted members are connected to piston mechanism, and by their back and forth movements will move the pistons in and out of cylinders to effect compression of air. The compression members will be so disposed about the crank shaft, that in their movements they will act to exert a counterbalancing action upon said shaft, rendering more constant torque in the shaft and reducing the peak load thereof.

The invention further consists in the features of construction and combination of parts hereinafter described and claimed.

In the drawings:

Figure 1 is a front view of the pump of the present invention;

Fig. 2, a cross section showing by means of full lines the pump mechanism in one thrown position, and by means of dotted lines the pump mechanism in neutral position;

Fig. 3, a view similar to Fig. 2, and showing the pump mechanism thrown into the opposite position from that shown in Fig. 2;

Fig. 4, a cross section through one of the cylinders showing the pistons and valve mechanisms;

Fig. 5, a bottom view of a cylinder and valve;

Fig. 6, a detail showing the means for moving the controlling valve of the cylinder as said cylinder is rocked back and forth; and

Fig. 7, a section on line 7-7 of Fig. 4, looking in the direction of the arrows.

Referring to the drawings, the device

comprises a crank shaft 7, which is journaled within a series of trusses or supports 55 8. Attached to each one of these crank shafts is a link 9; and each link in turn is connected to a plate-like supporting member 10. As shown in the drawings, there are six of the connecting links 9, and there are 60 six of the compressors and their supporting members; but since the construction and operation of each is similar, a detailed description of only one will be entered into, although the use of a plurality of these 65 pump mechanisms is desirable in carrying out the invention, as will appear hereinafter in the description.

The pump mechanism proper includes a supporting member 10, heretofore referred to. This member is mounted to rock about a hollow shaft 11, which is supported by the trusses or standards 8. The supporting member 10 is provided with upwardly extending members 12, which receive a cylinder 13; and the cylinder is secured to the member 12, and hence to the support 10, by means of straps 14, which are connected in any suitable manner to the members 12.

Rods 15, which as shown in the drawings 80 are two in number, pass through the members 12 with a sliding fit; and the ends of these rods are connected to the ends 16 of a weighted member 17, which member comprises the heavy or weighted ends 16 and the connecting portion 18, as shown in Figs. 2 and 3. Connected to each of the weighted ends 16 is a stem 19, one of which is joined to a piston 20, and the other of which is joined to a piston 21, both being mounted 90 within the interior of a cylinder 13. This cylinder, centrally thereof, is formed with a web 23, in which is mounted a rotatable controlling valve 24 provided with a right-angled port 25 and a circumferential groove 26, the latter extending approximately one quarter about the circumference of the valve. One end of this valve extends out beyond the casing; and the groove 26 is of sufficient length so that it extends into that portion 95 of the valve lying without the casing and thereby forms a passage for admitting outside air to the interior of the cylinder. Attached to this end of the valve is a bent finger 26a adapted to strike contacts 27 and 100 28 on a valve tripping member 29, which is

secured to one of the rods 15 and moves back and forth with the shifting of the weighted members, and therefore has a relative movement with respect to the cylinders, which is necessary to operate the valve.

Referring now to Figs. 2 and 3, the operation of this portion of the device will be described:

Assuming that motion is imparted to the 10 crank 7, and the supporting member 10, with the cylinder and its associated parts, is in the position shown by means of the dotted lines in Fig. 2, the first quarter revolution of the crank shaft will bring the parts into 15 the position shown by full lines in Fig. 2, and the weight of gravity will act to cause the weighted member 17 to descend into the position shown by full lines in Fig. 2, in which case the piston 20 will be placed in the 20 position shown in Fig. 4, and the piston 21 in the position shown in Fig. 4. The piston 20 will force the air within the cylinder out through the right angled port 25 in the valve 24, and into a main air collecting pipe 30, which is in communication with a supply 25 tank 31.

As the shaft continues to revolve, the next quarter revolution will bring the parts back into the position shown by means of dotted 30 lines in Fig. 2; and the next quarter revolution will bring the parts into the position shown in Fig. 3, wherein the weighted member 17 will again descend by the action of gravity, and in so descending force the piston 21 inward and the piston 20 outward.

In the meantime, the finger 26 on the valve 35 will have engaged with the contact 28, rotating the valve so as to bring it into communication with the passage 32 leading to the main air collecting pipe 30, and with the 40 passage 33 communicating with the interior of the cylinder, so that the air below the cylinder 21 will be forced out through the valve 25 and into the main air collecting pipe or header; and the groove 26 will be moved to be brought into communication 45 with the port 34, so that outside air will be sucked through said groove and into that portion of the cylinder in which the piston 20 is located.

The next quarter revolution brings the parts back to the dotted line position of Fig. 2, and the foregoing described operation is repeated.

It will be noted that the contact 29 is 55 mounted on the rod 15. This rod, as stated, has a movement relative to the cylinder 13, since it moves with the weighted member 17, and thus as said member makes its movement the valve is rotated accordingly, so as to place the port or passage therein in correct position for allowing the compressed air to flow into the header or gathering pipe and to admit outside air into that portion 60 of the cylinder in which the piston is moved.

outward. Said piston in so moving outward, of course, exerts a suction tending to pull the outside air in.

Reference has been made to the use of six of these pumping mechanisms. While, of course, it is not the intention of the invention to limit it to precisely that number, that is considered a very advantageous number to use, since the weighted members will be so distributed around the crank shaft as to 75 make a counterbalancing effect similar to the action of a fly-wheel. That is to say, while one of the weighted members is moving in a given direction, the others are placed in such position of angularity as to 80 counterbalance the force exerted by such weighted member on the crank shaft.

In the construction shown, power for operating the crank shaft is supplied by a motor 35 of any suitable type, which motor 85 drives a pulley 36, actuating a belt 37, driving a pulley 38 on a stub shaft 39, upon which stub shaft is mounted a fly-wheel 40, as well as a pinion 41. The pinion 41 meshes with a gear 42 attached to the crank shaft, 90 and by means of this motor and the connection described, sufficient power is imparted to the crank shaft to maintain it in movement. The tank is equipped with a gage 43, and when it is seen that the air within the 95 tank has for some reason or other decreased below the pressure desired, additional air may be placed therein by means of a hand operated pump 44.

Also, in starting the machine, it is necessary to create a certain amount of back pressure in the main air gathering pipe 32, otherwise the weighted members would descend with such force as to cause breakage. This back pressure acts as a cushion 105 against which the pistons must descend, and therefore the weighted members will drop with a gradual and steady movement, and without the shock or jar that would otherwise be incident thereto. Therefore, the 110 hand pump must be used to create sufficient pressure within the tank 31 to form this back pressure within the main air gathering pipe.

In place of using the motor 35, additional power may be supplied to the crank shaft 115 from other sources.

The invention as shown and described is susceptible of modification and is only deemed to be limited by the terms of the appended claims.

I claim:

1. A pump mechanism, comprising a crank shaft, a series of pivotally mounted cylinders, a connection between each of the cylinders and the crank shaft, pistons in opposite ends of each of said cylinders, a weighted shiftable member associated with each cylinder, a connection between each of said pistons and the weighted member associated therewith, said crank shaft when re- 125 130

volved rocking said cylinders, whereby said weighted members are moved by the action of gravity in correspondence with the rocking of the cylinders causing an in and out movement of said pistons, and said cylinders and weighted members in their movements exerting a counterbalancing action on the crank shaft, a main air collecting conduit communicating with the interior of each of said cylinders, a storage tank connected to the conduit, and power driven means for actuating said crank shaft, substantially as described.

2. A pump mechanism, comprising a crank shaft, a series of pivotally mounted cylinders, a connection between each of the cylinders and the crank shaft, pistons in opposite ends of each of said cylinders, a weighted shiftable member associated with each cylinder, a connection between each of said pistons and the weighted member associated therewith, said crank shaft when revolved rocking said cylinders, whereby said weighted members are moved by the action of gravity in correspondence with the rocking of the cylinders causing an in and out movement of said pistons, and said cylinders and weighted members in their movements exerting a counterbalancing action on the crank shaft, a main air collecting conduit communicating with the interior of each of said cylinders, a storage tank connected to the conduit, a power driven means for actuating said crank shaft, and means for producing an initial pressure within the tank to form a back pressure in the cylinders which cushions the action of the weighted members, substantially as described.

3. A pump mechanism, comprising a series of cylinders, piston mechanism associated with each cylinder, a shiftable weighted member associated with each cylinder and operatively connected to the piston mechanism thereof, a crank shaft, a pivotally mounted cylinder carrying member for each cylinder, a connection between the crank shaft and each of said carrying members, whereby said members are caused to rock as the crank shaft revolves, a mounting for each of the weighted members secured to its associated cylinder carrying member and on which the weighted member slides, said weighted member sliding by gravity as its cylinder carrying member is rocked, whereby said weighted members in their movements actuate the piston mechanisms associated therewith and exert a counterbalancing action on the crank shaft, and power driven means for actuating the crank shaft, substantially as described.

4. A pump mechanism, comprising a series of cylinders, piston mechanism associated with each cylinder, a shiftable slidable weighted member associated with each cylinder and piston mechanism and operatively

connected to the piston mechanism, a crank shaft, a pivotally mounted cylinder carrying member for each cylinder, a main air collecting conduit upon which said carrying members are pivotally mounted, a connection between the interior of the pipe and each of said cylinders, a storage tank and connection from said conduit to said tank, a connection between the crank shaft and each of said carrying members, whereby said members are caused to rock as the crank shaft revolves, a mounting for each of the weighted members secured to its associated cylinder carrying member and on which the weighted member slides, said weighted members sliding by gravity as the cylinder carrying members are rocked, and said weighted members in their movements actuating the piston mechanisms associated therewith and exerting a counterbalancing action on the crank shaft, and power driven means for actuating the crank shaft, substantially as described.

5. A pump mechanism, comprising a crank shaft, a series of pivotally mounted cylinders, a connection between each of the cylinders and the crank shaft, pistons in opposite ends of each of said cylinders, a weighted shiftable member associated with each cylinder, a connection between each of said pistons and the weighted member associated therewith, said crank shaft when revolved rocking said cylinders, whereby said weighted members are moved by the action of gravity in correspondence with the rocking of the cylinders causing an in and out movement of said pistons, and said cylinders and weighted members in their movements exerting a counterbalancing action on the crank shaft, a main air collecting conduit communicating with the interior of each of said cylinders, a storage tank connected to the conduit, power driven means for actuating said crank shaft, valve mechanism carried by each of the cylinders for establishing communication with one end of the cylinder and the collecting conduit and the other end of the cylinder and the outside air, and means for shifting said valve mechanism in accordance with the rocking of the cylinders, substantially as described.

6. A pump mechanism, comprising a crank shaft, a series of pivotally mounted cylinders, a connection between each of the cylinders and the crank shaft, pistons in opposite ends of each of said cylinders, a weighted shiftable member associated with each cylinder, a connection between each of said pistons and the weighted member associated therewith, said crank shaft when revolved rocking said cylinders, whereby said weighted members are moved by the action of gravity in correspondence with the rocking of the cylinders causing an in and out movement of said pistons, and said cylinders

and weighted members in their movements exerting a counterbalancing action on the crank shaft, a main air collecting conduit communicating with the interior of each of said cylinders, a storage tank connected to the conduit, power driven means for actuating said crank shaft, valve mechanism associated with each cylinder for establishing

communication with one end of the cylinder and the collecting conduit and between the other end of the cylinder and the outside air, and contact mechanism moving with said weighted members for actuating said valve in accordance with the rocking of the cylinders, substantially as described.

ANTHONY Z. MICIULIS.
